UNITED STATES PATENT OFFICE.

THAD S. KILGORE AND GEORGE W. WILSON, OF HENDERSON, IOWA.

BINDER ATTACHMENT.

1,357,711.

Specification of Letters Patent

Patented Nov. 2, 1920.

Application filed July 8, 1919. Serial No. 309,394.

To all whom it may concern:

Be it known that we, THAD S. KILGORE and GEORGE W. WILSON, citizens of the United States, and residents of Henderson, in the county of Mills and State of Iowa, have invented a certain new and useful Binder Attachment, of which the following is a specification.

The object of our invention is to provide the combination of a binder or other piece of operative mechanism adapted to be drawn across the ground with an engine operatively connected with the operative mechanism of the machine on which the engine is mounted.

Still a further object is to provide an engine especially adapted for use for running the operative mechanism of a binder or the like where the binder or otherwise is drawn across the ground by independent power, and to provide means for controlling the speed of the engine according to the speed of the advance of the binder or the like.

With these and other objects in view our invention consists in the construction, arrangement and combination of the various parts of the device, whereby the objects contemplated are attained, as hereinafter more fully set forth, pointed out in our claims and illustrated in the accompanying drawings, in which:

Figure 1 shows a side elevation of a portion of a binder having mounted thereon an engine and illustrating our invention.

Fig. 2 shows a vertical, sectional view of the gear casing at the lower part of the engine illustrating the arrangement of the worm gear and clutch, taken on the line 2-2 of Fig. 1.

Fig. 3 shows a detail view of the governor and the automatic fuel control mechanism.

Fig. 4 shows a detail view of part of the mechanism for controlling the governor.

Fig. 5 shows an enlarged, detail view of the throttle valve.

Fig. 6 shows a detail, sectional view taken on the line 6-6 of Fig. 3; and

Fig. 7 shows a detail view of part of the mechanism for manually controlling and regulating the action of the governor.

In the accompanying drawings we have used the reference numeral 10 to indicate generally the frame of a part of a grain binder shown.

We have shown the large traction wheel

11 and part of the operative mechanism 12 of the binder.

It is well known that the operative mechanism of the binder is ordinarily operated 60 from the tractor wheel.

It is our purpose to operate such mechanism from an engine mounted on the binder frame and to provide an engine which can be used for the purpose mentioned, or can 65 be removed from the binder and used for general purposes.

It will be understood that the binder may be drawn over the ground or by a tractor or 70 in any suitable way.

We have shown in the accompanying drawings an engine cylinder 13 below which is a crank case 14. The crank case 14 has a portion which projects laterally from the cylinder, and the engine is so arranged on 75 the binder that the crank case extends forwardly in the machine as illustrated in Fig. 1.

The crank shaft 16 is arranged fore-and-aft on the binder.

It may be mentioned in this connection that our device may be used in connection with a binder or other machine having operative mechanism.

Mounted in the forward lower portion of 85 the crank case 14 is a transverse shaft 17. On the crank shaft 16 is a worm 18 which meshes with a worm gear 19 loosely mounted on the shaft 17.

Formed on one side of the worm gear 19 90 is a clutch member 20.

Slidably but non-rotatably mounted on the shaft 17 is a sleeve 21, on which is formed a coacting clutch member 22.

The sleeve 21 has spaced annular ribs 23 between which project the arms 24 of a clutch shifting lever 25. On the crank shaft 16 is a fly wheel 26 which may also serve as a belt pulley.

It will be noted that the clutch members and gears heretofore described, except the fly wheel are all mounted within a suitable casing so that they may be run in oil for thorough lubrication.

On the shaft 17 outside the casing 14 is a sprocket 27 in line with an ordinary sprocket 28 on the binder, from which sprocket 28 the operative mechanism of the binder is run.

Ordinarily the sprocket 28 is operated 105 from the large sprocket 29 on the traction

wheel by means of a sprocket chain. That chain, where our engine is used, is removed from the sprocket 28 and is extended over a sprocket 30 on a shaft 31; said chains 5 being indicated by the reference numeral 32.

Suitably mounted is a shaft 33 on which is a sprocket gear 34. On the shaft 31 is a sprocket 35 shown in dotted lines in Fig. 1, alined with the sprocket 34. A chain 36 10 travels on the sprockets 34 and 35.

Mounted in suitable bearings on the engine frame is a shaft 37 arranged at right angles to the shaft 33.

On the shaft 33 is a beveled gear 38 which 15 meshes with a beveled gear 39 on the shaft 37.

Fixed on the shaft 37 is a collar 40, to which are pivoted opposite links 41.

Slidably mounted on the shaft 37 is a 20 sleeve 42 having an annular groove 43 therein. Pivoted to the sleeve 42 are opposite links 44. The respective links 44 and 41 are pivoted to governor balls 45.

Mounted on the shaft 37 between the collar 40 and the sleeve 42 is a coil spring 46 25 which normally tends to force the sleeve 42 away from the collar 40 and hold the governor balls adjacent to the shaft 27.

A fuel supply tube 47 leads from the 30 carbureter 48 to the engine and has mounted thereon on a stem 49 a throttle valve 50 of the butterfly type.

On the stem 49 is an arm 51. Suitably pivoted on the engine frame at 52 between 35 its ends is a lever 53. One end of the lever 53 is projected into the groove 43 and the other end is pivoted to the arm 51, as illustrated in Figs. 1 and 3.

Slidably extended through the lever 53 40 is a link 54, which is pivoted at one end to a controlling lever 55, arranged adjacent to the driver's seat 56.

On the link 54 on opposite sides of the lever 53 and spaced therefrom are collars 45 57 and 58. On the link 54 between the lever 53 and the collar 57 is a coil spring 59, and on said link between the lever 53 and the collar 58 is a coil spring 60.

We will now describe the practical operation 50 of our improved device.

Assume that the lever 55 is set in what may be called neutral position, where the springs 60 and 59 exert yielding tension on the lever 53, then when the binder or other 55 piece of machinery is drawn forwardly by independent power and the engine is operated for running the operative mechanism of the binder, it will be seen that the governor will be operated according to the speed 60 of advance of the binder.

In the particular form of our invention illustrated in the drawings we have shown mechanism for connecting the governor with the traction wheel 11.

65 It will, of course, be understood that any

mechanism which would operate the governor according to the advancing movement of the binder would carry out the purpose of our invention.

The parts are so set originally that when 70 the engine is operated and the binder is not moving the engine can be run. When, however, the binder is advancing, the movement of the governor balls outwardly will actuate the lever 53 for opening the throttle and 75 the throttle will continue to be actuated according to the speed of advance of the binder.

Owing to the fact that the load on the engine will vary according to the condition 80 of the grain being cut and so on, it is seen that it is desirable to have additional means for controlling the throttle, and this additional means is provided by the lever 55 and the parts connected therewith.

It will be readily understood that the lever 55 may be readily adjusted so that the action of the springs 60 and 59 substantially neutralize each other, or said lever may be set so that the action on said springs is such as 90 to modify what would otherwise be the operation of the governor. Thus a great many modifications may be produced.

It is also obvious that in many cases it is preferable to set the lever and leave it 95 in one position. In some cases, however, as where the grain in one part of the field is very heavy, and in another is light, it is desirable to make adjustments quickly during the operation of the binder. This 100 the operator can accomplish by simply shifting the lever 55.

The advantages of a structure such as 105 that herein shown may be largely seen from the foregoing description.

The engine frame is provided with brackets 61 and 62 for supporting the engine frame of the binder frame, and also for supporting the engine if it is removed from the binder.

It will thus be seen that in the engine structure herein described, we have provided a power plant which is especially adapted for use on a binder or the like, but which may be used as an independent power plant. 115

The advantage of running an engine according to the speed of advance of the binder is obvious.

On the engine shaft 16 and the shaft 37 I have mounted sprocket gears 63 and 64 120 adapted to receive a chain, whereby the governor device may be operated according to the speed of the engine, where the engine is removed from the binder and it is desired to maintain the engine at a certain predetermined speed.

Changes may be made in the construction and arrangement of the parts of our device without departing from the essential features and purposes of our invention, 130

and it is our intention to cover by our claims any modified forms of structure or use of mechanical equivalents, which may be included within their scope.

5 We claim as our invention:

1. The combination of a machine having wheels for traveling over the ground and having operative mechanism, an internal combustion engine supported on said machine, provided with a carburetor and with a throttle located between the carburetor and the engine cylinders; means for operatively connecting said engine with said mechanism; a governor device; means connected 15 with said governor device and with one of said wheels for operating said governor device according to the speed of advance of said machine over the ground; means for operatively connecting said governor device 20 with said throttle; and means on said machine adapted in one position for controlling said throttle independently of said governor and in another position to regulate the action of said governor.
2. The combination of a machine having an operative mechanism, with an engine thereon for operating the said mechanism, a fuel supply device for said engine, a governor device connected with said machine 25 for operation according to the speed of advance of said machine over the ground, a throttle valve for controlling the supply of

fuel to the engine, means for connecting said governor device with said throttle, and means adapted for controlling said throttle 35 independently of said governor, and adjustable to position for regulating the action of said governor on the throttle.

3. The combination of a machine having an operative mechanism, with an engine 40 thereon for operating the said mechanism, a fuel supply device for said engine, a governor device connected with said machine for operation according to the speed of advance of said machine over the ground, a 45 throttle valve for controlling the supply of fuel to the engine, means for connecting said governor device with said throttle, and means adapted for controlling said throttle independently of said governor, and adjustable to position for regulating the action 50 of said governor on the throttle, said means including a lever pivoted on said machine, having one portion operatively connected with said governor, another portion operatively connected with said throttle, a lever 55 adapted to fit in a variety of positions, and means for yieldingly, adjustably connecting said lever with said first lever for yielding in different directions depending upon the 60 position of the last described lever.

Des Moines, Iowa, June 14, 1919.

THAD S. KILGORE.
GEO. W. WILSON.
